US00D940946S

(12) **United States Design Patent** (10) **Patent No.:** **US D940,946 S**
(45) **Date of Patent:** **** Jan. 11, 2022**

(54) **LED LIGHT**

(71) Applicants: **Yaoping Xu**, Changzhou (CN);
Changzhou KAISEN Photoelectricity
Co., Ltd., Changzhou (CN)

(72) Inventor: **Yaoping Xu**, Changzhou (CN)

(73) Assignees: **CHANGZHOU KAISEN**
PHOTOELECTRICITY CO., LTD.,
Changzhou (CN); **Yaoping Xu**,
Changzhou (CN)

(**) Term: **15 Years**

(21) Appl. No.: **29/706,355**

(22) Filed: **Sep. 19, 2019**

(51) LOC (13) Cl. **26-04**

(52) U.S. Cl.

USPC **D26/76**; D26/72

(58) **Field of Classification Search**

(57) **CLAIM**

The ornamental design for an LED light, as shown and described.

DESCRIPTION

FIG. 1 is a perspective view of an LED light showing my new design;

FIG. 2 is a front elevational view thereof;

FIG. 3 is a rear elevational view thereof;

FIG. 4 is a left-side view thereof;

FIG. 5 is a right-side view thereof;

FIG. 6 is a top plan view thereof; and,

FIG. 7 is a bottom plan view thereof.

The broken lines illustrate portions of the LED light which form no part of the claimed design.

1 Claim, 7 Drawing Sheets
